[57] CLAIM

The ornamental design for a bicycle handlebar, as shown and described.

DESCRIPTION

FIG. 1 is a perspective view of a bicycle handlebar embodying my new design;

FIG. 2 is a front elevational view thereof on a reduced scale;

FIG. 3 is a rear elevational view thereof on a reduced scale;

FIG. 4 is a top plan view thereof on a reduced scale;

FIG. 5 is an end elevational view of one end thereof on a reduced scale, the opposite end being a mirror image thereof;

FIG. 6 is a bottom plan view thereof on a reduced scale;

FIG. 7 is an enlarged cross-sectional view thereof taken on line 7—7 of FIG. 1;

FIG. 8 is a perspective view of a bicycle handlebar showing a second embodiment of my design;

FIG. 9 is a front elevational view of FIG. 8 on a reduced scale;

FIG. 10 is a rear elevational view of FIG. 8 on a reduced scale;

FIG. 11 is a top plan view of FIG. 8 on a reduced scale;

FIG. 12 is an end elevational view of FIG. 8 on a reduced scale, the opposite end being a mirror image thereof;

FIG. 13 is a bottom plan view of FIG. 8 on a reduced scale.

The characteristic feature of my new design resides in the v-shaped channel in the center portion of the top crossbar of the handlebar.
